UNITED STATES PATENT OFFICE.

GEORG SPIESS, OF LEIPZIG-REUDNITZ, GERMANY.

DEVICE FOR GATHERING SHEETS TO FORM PERIODICALS AND THE LIKE.

1,294,842.

Specification of Letters Patent. Patented Feb. 18, 1919.

Application filed November 27, 1915. Serial No. 63,740.

To all whom it may concern:

Be it known that I, GEORG SPIESS, a citizen of the German Empire, and a resident of Leipzig-Reudnitz, in the Empire of Germany, have invented certain new and useful Improvements in Devices for Gathering Sheets to Form Periodicals and the like, of which the following is a specification.

10 This invention has reference to improvements in devices for gathering sheets to form periodicals, to assemble sheets of music, newspapers and the like.

15 Heretofore machines for piling single sheets of paper were known. These machines arrange the sheets in the folded condition, one on top of the other, according to their successive numbers so that the sheets are gathered in proper successive order for 20 being further worked up. If printed and folded sheets are gathered to form periodicals or sheets of music assembled or newspapers and united by binding, then it is necessary to unfold the sheets and gather them 25 in the unfolded condition.

According to the present invention the described purposes are attained by means of mechanical devices. The folded sheets which are vertically arranged one behind the other 30 are seized, one after the other, on one single thickness of paper or leaf by a transport device and held solely on this one leaf during the transportation. Each moving sheet thus is allowed to unfold and spread whereupon 35 the transported sheets are deposited, in the unfolded condition, one on top of the other.

It is known to assemble folded sheets which shall be bound in such manner that the inner front sheet of the vertical stack is 40 somewhat opened by means of a pneumatic suction device and transported in this condition to the pile table which forms a V-shaped saddle. This arrangement, however, suffers from the defect that the sheets have 45 the tendency to fold again and therefore special devices must be employed to protect the assembled sheets against re-folding.

The described defect has been overcome by the present invention, illustrated in the 50 accompanying drawing in which:

Figure 1 represents in side elevation with some parts in section a machine for unfolding and gathering sheets for forming periodicals and the like.

55 Fig. 2 shows the machine in top plan view.

Similar characters of reference denote like parts in all the figures.

In the machine illustrated a device for gathering sheets is employed by means of which the inner front sheet is separated by 60 a pneumatic suction device and then mechanically transported to the table upon which the pile is formed. The stack of sheets A is vertically arranged upon the stack table B. Before the inner front of 65 the stack a swinging member C is provided which serves as a support for the pneumatic suction pipe D. The swinging member C may be cylindrical or partly cylindrical and the stack of sheets rests against the 70 outer surface of the same. An ascending and descending swinging motion is imparted to the member C from a crank disk E by means of a crank rod F.

A sheet separated from the stack by the 75 pneumatic suction pipe D is transported in an upward direction. When in the horizontal top plane which the sheet may reach it is seized by a gripper G which is attached to a carriage H. The gripper carriage receives 80 a to and fro motion by means of an endless chain I or a similar device. The swinging to and fro motion also is imparted to the gripper carriage from the crank disk E by means of the crank rod K. The crank rod 85 transmits the motion to the sprocket wheel L so that the wheel imparts a to and fro motion to the gripper carriage H in a direction opposite to the movement of the swinging member C. The chain to which the 90 gripper carriage H is attached is guided over guiding rollers I¹, I².

In accordance with the present invention the folded sheets of the stack A are so arranged upon the stack table B that their 95 open ends are on the top. This renders it possible that the pneumatic suction pipe D acts only on the inner front leaf of a folded sheet. The pneumatic pipe D now performs an ascending movement during which this 100 leaf of the sheet alone will rest against the surface of the swinging member C while the second leaf of the sheet unfolds and the upper end of the first sheet transported by the pneumatic pipe is seized by the gripper 105 G. The gripper carriage with the gripper thereon now transports the unfolded sheet and deposits it upon the pile table M. In order to facilitate the unfolding of the sheet spreading arms R are provided above the 110

stack of folded sheets A. The sheet spreading arms reach into the sheets to be unfolded so that during further transportation of the sheet the second leaf must slide underneath the sheet spreading arms. If now the various sheets have been deposited upon the pile table M in the described manner then the sheets are further transported, step by step, and gathered one on top of the other in known manner. The sheets being in the unfolded condition accordingly are assembled while unfolded.

A number of unfolded sheets gathered as described to form a periodical may be directly bound at the end of the pile table M. For this purpose the device illustrated is provided with binding heads N located underneath the pile table M and counter binding members O are mounted above the table. The gathered sheets between these heads N and binding members O are bound by this arrangement shortly before leaving the table and thus form a finished periodical which is closed and brought upon the table P.

The pneumatic suction device for separating the inner leaf of each folded sheet and transporting it may be varied in the details of construction without departing from the spirit of this invention and a mechanical transport may be applied.

The described machine may be used for forming bound or unbound periodicals. In each instance the sheets which have been gathered in an unfolded condition are closed during the last phase of the method by hand or mechanically.

I claim as my invention:

1. A machine for gathering sheets to form periodicals and the like comprising a stack table with folded sheets thereon having their open ends at the top, means for raising the inner leaf of each folded sheet thus allowing

it to partially open itself, and sheet spreading arms reaching between both leaves of the sheet whereby the unfolding is completed.

2. A machine for gathering sheets to form periodicals and the like comprising a stack table with folded sheets thereon having their open ends at the top, a movable pneumatic suction device acting only on the inner leaf of a sheet and raising it, and sheet spreading arms reaching between both leaves of the sheet allowing the second leaf to pass underneath it whereby said second leaf is completely spread out.

3. A machine for gathering sheets to form periodicals and the like comprising a stack table with folded sheets thereon, having their open ends at the top, means for raising the inner leaf of each folded sheet thus allowing it to partially open itself, sheet spreading arms reaching between both leaves of the sheet whereby the unfolding is completed, and means for depositing the sheets while in the spread out and open condition.

4. A machine for gathering sheets to form periodicals and the like comprising a stack table with folded sheets thereon having their open ends on the top, a movable pneumatic suction device acting only on the inner leaf of a sheet and raising it, and sheet spreading arms reaching between both leaves of the sheet for completely spreading out the second leaf, means for transporting the unfolded sheets, means for gathering the sheets to form periodicals and means for binding and collecting the finished periodicals.

Signed at Leipzig, Germany, this 2d day of November, 1915.

GEORG SPIESS.
